UNITED STATES PATENT OFFICE.

LEVI SHELL, OF SIBLEY, IOWA.

BRICK-MOLDING MACHINE.

No. 800,500.

Specification of Letters Patent.

Patented Sept. 26, 1905.

Application filed July 25, 1904. Serial No. 218,080.

To all whom it may concern:

Be it known that I, LEVI SHELL, a citizen of the United States, residing at Sibley, in the county of Osceola and State of Iowa, 5 have invented a new and useful Brick-Molding Machine, of which the following is a specification.

This invention relates to an improved brick-machine, and has for its object to provide an 10 inexpensive, durable, and efficient machine of this character by means of which bricks, tiles, building-blocks, and similar articles may be conveniently and rapidly manufactured.

A further object of the invention is to provide a tamping-carriage mounted on the bed of the machine and movable to operable position above the mold-box, so that after the mold-box has been filled the cement, concrete, or other material may be thoroughly tamped 20 and the carriage withdrawn to permit the removal of the molded product.

A still further object is to provide the mold-box with a plurality of division plates or partitions, so that a number of bricks or tiles 25 may be formed at each operation of the machine, and, further, to provide means for ejecting said bricks or tiles without chipping or otherwise injuring the same.

The invention consists in the construction 30 and novel combination and arrangement of parts hereinafter fully described, illustrated in the accompanying drawings, and pointed out in the claims hereto appended, it being understood that various changes in form, proportion, and minor details of construction 35 may be resorted to without departing from the principle or sacrificing any of the advantages of this invention.

In the accompanying drawings, forming 40 a part of this specification, Figure 1 is a perspective view of a brick-machine constructed in accordance with my invention and showing the tamping-carriage in position over the mold-box. Fig. 2 is a longitudinal sectional view. Fig. 3 is a transverse sectional view. Fig. 4 is a perspective view of one of the mold-trays detached. Fig. 5 is a perspective view of a portion of the machine, showing the mold-tray removed.

50 Similar numerals of reference indicate corresponding parts in all the figures of the drawings.

In constructing the machine I provide a supporting frame or table formed of wood, 55 metal, or other suitable material and consisting of the uprights 5, to which are bolted or

otherwise rigidly secured longitudinal beams 6. Secured to the uprights 5 is the table-top 7, having a rectangular opening 8 formed therein, as shown, and disposed beneath said opening and supported by a horizontal bar 9 is the mold-box 10. The mold-box 10 is provided with a series of division plates or partitions 11, the ends of which are spaced from the side walls of the box, as indicated at 12, 60 and slidably mounted in said box is a removable tray 13, which forms the bottom of the mold, as shown. The tray 13 is provided with a plurality of spaced openings 14, adapted to receive the division plates or partitions 11, 65 so that when said tray is in position the box will be divided into a series of molding chambers or compartments 15. The tray 13 is designed to support the bricks or tiles after the latter have been ejected from the mold-box, as clearly shown in Fig. 3 of the drawings, said tray being provided with a removable front wall 16 and removable rear and end walls 17, so as to permit the bricks to be 70 readily detached from the tray without chipping or otherwise marring the same.

Slidably mounted in suitable guides 18 are plungers 19 for elevating the tray 13 and ejecting the bricks from the mold-box, said plungers being connected by a horizontal bar 85 or rod 20 and operated through the medium of a foot-lever 21, pivoted, as shown at 22, to one of the longitudinal beams of the supporting frame or table. The plungers 19 are also connected by a brace-rod 23 to the foot-lever 90 21, and are each provided with spaced ejecting-rods 19' and a laterally-projecting block or stop 24, which engages a cross-bar 25 and serves to limit the downward movement of said plungers.

95 Secured to the rear end of the supporting frame or table are brackets 26, upon which is mounted for travel a reciprocating tamping-carriage 27. The carriage consists of a horizontally-disposed bar 28, to which is pivoted, as indicated at 29, a pair of rearwardly-extending inclined bars 30, the opposite ends of which are rigidly secured to a bar or axle 31, provided with terminal wheels or rollers 32. The wheels or rollers 32 travel in grooves or 100 guides 33, formed in the brackets 26, so as to permit the carriage to be moved forward over the mold-box when filling the latter, as will be more fully explained hereinafter. The horizontal bar 28 is provided with terminal 105 handles 34 and a plurality of intermediate tamping teeth or plungers 35, corresponding 110

in number to the molding chambers or compartments 15, so that when the carriage is moved forward to a position directly over the mold-box and the bar 28 swung downwardly 5 on its pivotal connection one tooth will enter each of the molding-compartments and thoroughly tamp the cement, concrete, or other material contained therein. The tamping-teeth or plungers 35 are provided with enlarged heads 36 and reduced threaded extensions 37, which enter openings formed in the bar 28, and are rigidly secured therein by clamping-nuts 38. The tamping-carriage is pivoted on the wheels or rollers 32 of the axle 15 31, and a brace-bar 39 preferably connects said axle and the inclined bars 30 in order to insure additional rigidity to the frame of said carriage. The rear uprights 5 are preferably extended a short distance above the table-top, 20 as indicated at 40, to form a rest or support 41 for the horizontal bar 28, so that when the carriage is moved backward and the terminal handles 34 brought into engagement with said uprights the tamping-carriage will be supported in inoperative position, thereby permitting the bricks to be readily ejected from the mold-box.

In operation the tray 13 is introduced in the mold-box and the compartments formed by 30 the division plates or partitions partly filled with cement, concrete, or other material of which the bricks are to be formed. The tamping-carriage is then moved forward to a position directly over the mold-box and the 35 concrete thoroughly tamped in the several compartments by reciprocating the bar 28 on its pivotal connection, after which more concrete is introduced in the compartments and the tamping operation continued, the surplus 40 material being subsequently removed with a trowel or straight-edge in the usual manner. The tamping-carriage is then moved rearwardly and the bricks ejected from the mold by depressing the foot-lever, which operation 45 elevates the tray to the position shown in Fig. 3 of the drawings. The removable side and end pieces of the tray are detached and said tray placed upon a table or other suitable support designed to receive the same, after 50 which a pallet is placed upon the top of the bricks and the tray reversed, leaving the bricks on the pallet and in position to be removed to the drying-racks until sufficiently hard for use.

55 If desired, the bricks or tiles may be formed with an exterior finish in imitation of chipped rock or other ornamental designs by inserting a pattern-plate in the bottom of each of the molding-compartments, as will be readily understood.

Having thus described the invention, what is claimed is—

1. In a brick-machine, the combination with a frame, of a mold, and a tamping element

movable laterally to and from the mold and free to swing in a vertical plane.

2. In a brick-machine, the combination with a frame, of a mold, and a tamping element movable in a substantially horizontal plane to and from the mold and capable of free swing- 70 ing movement in a vertical plane.

3. In a brick-machine, the combination with a frame, of a mold, a tamping element movable laterally to and from the mold and free to swing in a vertical plane, and means for 75 elevating the mold.

4. In a brick-machine, the combination with a frame, of a mold, a tamping element movable laterally to and from the mold and free to swing in a vertical plane, and means for 80 supporting the tamping element in inoperative position.

5. In a brick-machine, the combination with a frame, of a mold, a tamping element movable laterally to and from the mold and free to swing in a vertical plane above the latter, 85 and means for supporting the tamping element in inoperative position.

6. In a brick-machine, a mold provided with a plurality of molding chambers or compartments, a tamping-carriage movable in a substantially horizontal plane to and from the mold, and a tamping element pivoted to the carriage and capable of free swinging movement in a vertical plane.

7. In a brick-machine, a mold, a tray supported within the mold and forming the bottom of the latter, a tamping element movable laterally to and from the mold and free to swing in a vertical plane, and means for 100 elevating the tray.

8. In a brick-machine, a mold, a removable tray forming the bottom of the mold and provided with detachable side and end walls, a tamping element movable laterally to and from the mold and free to swing in a vertical plane, and means for elevating the tray.

9. In a brick-machine, a mold provided with a plurality of division plates or partitions, a removable tray having detachable side and end walls supported in the mold and provided with a plurality of spaced slots adapted to receive said partitions, and means for elevating the tray.

10. In a brick-machine, a mold provided with a plurality of division plates or partitions, a removable tray supported within the mold and provided with a plurality of spaced openings adapted to receive said partitions, a freely-swinging tamping element movable laterally to and from the mold, and means for elevating the tray.

11. In a brick-machine, the combination with a frame, of a mold, a tamping-carriage mounted for travel on the frame, a tamping element pivoted to the carriage, and means for supporting said tamping element in inoperative position.

12. In a brick - machine, the combination with a frame, of a mold, guides secured to the frame, a reciprocating tamping - carriage mounted for travel on said guides, and a tamping element pivoted to the carriage and free to swing in a vertical plane. 40
13. In a brick - machine, the combination with a table having an opening in the top thereof, a mold seated in said opening, a tray supported by the mold and forming the bottom thereof, plungers arranged beneath the mold and adapted to engage the tray, means for operating the plungers to elevate said tray, and a tamping element free to swing in a vertical plane and having a freely - movable pivotal support. 45
14. In a brick - machine, the combination with a table having an opening in the top thereof, a mold seated in said opening and arranged flush with the top of the table, a tamping-carriage mounted for travel on said table and adjustable to operative position above the mold, a tamping element pivoted to the carriage, and means for supporting said tamping element in inoperative position. 50
15. In a brick - machine, the combination with a table, of a mold, brackets secured to the table, a tamping-carriage mounted for travel on said brackets and adjustable to operative position above the mold, and uprights secured to the table for supporting the carriage in inoperative position. 55
16. In a brick - machine, the combination with a table, of a mold, brackets provided with grooves or channels secured to the table, wheels mounted for travel in said grooves or channels, an axle connecting said wheels, rods secured to the axle, and a horizontally-disposed 60
- bar pivoted to said rods and provided with a plurality of tamping-teeth. 65
17. In a brick - machine, the combination with a table, of a mold, a manually-operated tamping-carriage movable laterally to and from the mold, and a tamping element pivoted to said carriage. 70
18. In a brick - machine, the combination with a table, of a mold, guides secured to the table, wheels mounted for travel in said guides, and a tamping-frame pivoted to said wheels and free to swing in a vertical plane 75
- above the mold. 80
19. In a brick - machine, the combination with a frame, of a mold, a carriage mounted for travel on the frame, and a tamping element pivoted to the carriage and capable of free swinging movement above the mold. 85
20. In a brick - machine, the combination with a frame, of a mold, a carriage mounted for horizontal travel on the frame, and a plurality of tamping-plungers pivoted to the carriage and capable of free swinging movement in a vertical plane above the mold. 90
21. In a brick-machine, a tamping device free to swing in a vertical plane and having a freely-movable pivoted support. 95
22. In a brick-machine, a tamping device free to swing in a vertical plane, and a supporting means freely movable in an approximately horizontal plane. 100

In testimony that I claim the foregoing as my own I have hereto affixed my signature in the presence of two witnesses.

LEVI SHELL.
